UNITED STATES PATENT OFFICE.

WILLIAM S. MCFERREN, OF NEW FRANKLIN, PENNSYLVANIA, ASSIGNOR
OF ONE-THIRD TO HARRY R. MCFERREN, OF SAME PLACE.

SPRING-CLEVIS FOR PLOWS.

SPECIFICATION forming part of Letters Patent No. 668,925, dated February 26, 1901.

Application filed December 22, 1900. Serial No. 40,752. (No model.)

To all whom it may concern:

Be it known that I, WILLIAM S. MCFERREN, a citizen of the United States, residing at New Franklin, in the county of Franklin and State 5 of Pennsylvania, have invented new and useful Improvements in Spring-Clevises for Plows, of which the following is a specification.

My invention relates to spring-clevises for 10 plows; and the object of the same is to produce a device of this character which can be attached to a plow to relieve the sudden strain caused by the striking of the plow-point against some obstruction, such as a concealed 15 stone or stump. With this object in view I have devised the simple and novel construction which is fully described in this specification and claimed, and illustrated in the accompanying drawings, forming a part thereof, 20 in which—

Figure 1 is a side elevation of my device with part broken away. Fig. 2 is an end elevation of the same.

Like numerals of reference designate like 25 parts in both views of the drawings.

The numeral 1 designates an integral head which has perforated cheeks 2 and rearwardly-extending arms 3, pivoted on a cross-pin 4, which extends transversely through the forward end of a plow-beam 5. By this arrangement the head is free to move about the pin 4 as an axis. A series of perforations 2^a in the cheeks 2 allow a range of adjustment for a clevis 6, which is pivoted on a pin 7', extending through two of the perforations 2^a. 35 The back of the clevis 6 is also provided with a set of perforations 6^a, which furnish attachment for a second clevis 7, to which the double-tree is attached. To provide a bearing on the head 1 for a spring 8, a cross-bar 9 is secured between the upper portion of the two cheeks 2. On this bar 9 is mounted a dish-faced disk 10, within which fits the lower end of the spiral spring 8. The upper end of the 40 spring 8 bears against a cross-bar 11, which is adjustably mounted on the arms 12 of a yoke 13. The adjustment of the bar is accomplished by nuts 12^a, fitted on the ends of the arms 12, and the yoke is secured to the 45 under side of the beam 5 by a bolt 14, passed through an aperture in the cross-bar 15 of the yoke. Space enough is left between the beam 5 and the arms 12 to permit the move-

ment of the arms 3; but the downward movement is limited by the bar 15. To make my 55 structure complete, some details are added in the shape of a brace 16, bearing on a cross-bar 17, connecting the arms 12, and a rod 18, footed in the disk 10 and bar 9 and mounted to slide in the cross-bar 11. This rod 18 serves as a 60 guide and also secures the spring 8, which surrounds it, against sidewise displacement.

When in use, the team is hitched to the clevis 7, as before stated. The spring 8 is adjusted by the nuts 12^a to a compression equal 65 to a normal pull of the team. Therefore any unusual strain which is brought to bear on the clevis by the plows striking an obstacle, as before mentioned, will compress the spring. The head 1 will be rotated about its axis, 70 thereby relieving the strain on the beam 5. After the crisis has passed the spring 8 will restore the head to its normal position in contact with the bar 15.

I do not wish to be limited as to details of 75 construction, as these may be modified in many particulars without departing from the spirit of my invention.

Having thus described my invention, what I claim as new, and wish to secure by Letters 80 Patent, is—

1. The combination, substantially as described, with a plow-beam, of a head pivoted to the forward end of said beam, a yoke rigidly secured to said beam, a bar adjustably 85 mounted on the arms of said yoke, and a spring bearing at one end against said yoke and at the other end against said head.
2. The combination, substantially as described, with a plow-beam, of a head having 90 rearwardly-extending arms pivoted to the forward end of said plow-beam, a yoke mounted on said plow-beam and having upwardly-extending arms, said yoke being positioned to limit the movement of said head in one 95 direction, a bar adjustably mounted on the said arms of said yoke, and a spring bearing at one end against said head and at the other end against said bar.

In testimony whereof I have hereunto set 100 my hand in presence of two subscribing witnesses.

WILLIAM S. MCFERREN.
